BOTTLE BUFFING MACHINE

August J. Weiss, Baltimore, Md., assignor to
 Maryland Glass Corporation, Baltimore, Md., a
 corporation of Maryland

Application February 6, 1939, Serial No. 254,932

8 Claims. (Cl. 51—93)

This invention relates to improvements in buffing or polishing machines, and it is particularly concerned with the polishing of bottles in the glass factory prior to packaging and shipping. The bottles particularly in mind are quite small and are commonly used as perfume containers. This statement, however, is not to be regarded as a limitation upon the use of the invention because the principles of the latter would apply just as well in buffing or polishing bottles of a larger size as well as glass-ware of shapes other than that of bottles.

As the latter come from the molds they can be observed as being somewhat rough in surface. The surface is not rough to the touch, but there are minute unevennesses which mar the appearance of the bottle and which can readily be eliminated by the simple buffing or polishing operation which the instant machine performs.

In many instances the latter operation is done by a workman who is required to press the bottle board or rack up against the buffing wheel until the required polish has been achieved. To do this from morning to evening puts the workman under a severe abdominal muscular strain which eventually culminates in some type of occupational disease. The machine is contrived to do the heavy work, leaving the workman to the lighter task of filling and changing bottle racks and supplying the buffing material.

The conventional mode of polishing comprises the holding of the bottle rack against the buffing wheel and imparting a reciprocation to said rack along straight up and down lines, that is to say, lines parallel to a plane standing at right angle to the axis of the buffing wheel. This has the result of applying the buffing pressure in rectilinear strokes which impair the buffing operation, especially if the buffing wheel consists of layers of felt, because then the slight tendency of the felts to separate produces medial zones which are lacking in a full polishing effect. With this preamble in mind the objects of the invention are as follow:

First, to provide a machine for buffing or polishing glassware, more specifically small perfume and similar bottles, to give them a smooth, satin finish that will greatly improve their appearance and make them much more acceptable than if marketed in their comparatively rough state.

Second, to provide a bottle buffing machine which in its operation is adapted to eliminate the heavy abdominal muscular strains to which a

workman is commonly subjected in carrying out the buffing operation by hand.

Third, to provide a bottle buffing machine wherein the carrier comprises a complete and self-contained unit, having included therein every element necessary to the reciprocation of the bottle rack, said carrier, therefore, being independent of the frame excepting for support.

Fourth, to provide a bottle buffing machine wherein the buffing operation has a bias reciprocation as the ultimate and essential motion of the bottle rack, thereby shifting the bottles along short diagonal strokes across the faces of the felts, thus lessening the possibility of spreading the felts and virtually eliminating poor polishing by the occurrence of voids between the felts.

Other objects and advantages will appear in the following specification, reference being had to the accompanying drawings, in which:

20 Figure 1 is a plan view of the bottle buffing machine.

Figure 2 is a perspective view of the bottle board or rack showing a number of bottles in place.

25 Figure 3 is a fractional perspective view of the carrier.

Figure 4 is a side elevation of the machine.

Figure 5 is a detail side elevation particularly illustrating the cable attachments to the carrier.

In carrying out the invention provision is made of a frame generally designated 1. This frame may comprise any suitable type of support for the carrier, but the most convenient form of a support is that of the table shown. To this end the frame consists of legs 2, cross braced at 3 and carrying a top 4 to which virtually all of the mechanism is either directly attached or from which it is suspended.

The table top 4 is cut out at 5 to make room for a box 6. The main purpose of this box is to catch the surplus buffing compound. Its sides have upward extensions 7 (Fig. 9) which meet the top edge of the enlarged front 8 which, because of said enlargement, constitutes an apron to shield the workman to some extent. The box 6 is secured to the table top 4 in any desired way, for example by means of bent straps 9. The ends of these straps are secured beneath the top and the box is rested therein as shown (Fig. 12).

A trough 10 has a lip 11 overhanging the back of the box 6 (Fig. 9). This trough is supported in any convenient way beneath the buffing wheel generally designated 12. The frame 1 carries metal bars 13 (Fig. 12). These are secured to the top 4 a slight distance beyond the side margins of the cut-out 5. Each of the bars has a pair of rigidly upstanding standards 14, 15. These standards carry pairs of rails 16, 17 (Fig. 12).

The bottom rail 17 constitutes a track in each instance. The top rails 16 comprise guard rails. The guard rails and tracks are secured to the standards 14, 15 by bolts 18. These bolts are screwed into the rails at 19 (Fig. 19) after passing through spacers 20 which hold the rails off from the standards the desired distance. In the instance of the top rails the bolts 18 also pass through shields 21 which are thus secured in place.

It will be understood from Fig. 19 that the track 17 and guard rail 16 are stationary. This is true of both sets of tracks and guard rails. The shields 21 are chiefly for the purpose of preventing the workman from getting his hands caught in certain moving parts. Before describing these parts it is desired to carry out the description of the previously mentioned buffing wheel 12.

This wheel, shown in Fig. 18, consists of a large number of felt disks 22. Felt happens to be the material used in the instant installation because it has been found best suited to the purpose. Each disk is fairly thick and as a consequence it has sufficient mechanical strength to stand up under the pressure of the bottles. These disks are assembled on a sleeve 23 which like the backing washer 24 abuts a collar 25 on the mandrel 26.

The sleeve 23 is secured to the mandrel by a key 27. That end of the sleeve 23 opposite to the abutment collar 25 is threaded at 28. A nut 29 with spanner wrench holes is screwed upon these threads against a follower washer 30 which thus clamps the disks in tight assemblage. The contiguous portion of the mandrel 26 is threaded at 31, then terminating in an end 32 which is revolvable in a bearing 33. A nut 34 is screwed onto the threads 31 into tight engagement with the end of the sleeve 23. The latter is thus held firmly on the mandrel.

The other end 35 of the mandrel 26, that is to say the end opposite to 32, is supported by a bearing 36 (Fig. 1). Said end carries a triple

pulley 37 which is belted at 38 to a triple drive pulley 39 on the shaft of a motor 40. This motor is desirably mounted on the floor (Fig. 4) inasmuch as it is fairly heavy and moreover would require more room than the table top 4 can reasonably be made to afford.

Further appurtenances of the frame 1 comprise brackets 41, 42. The forward pair 41 is upstanding from the table top 4 (Fig. 4). The rearward pair 42 juts out horizontally, being attached in any convenient way. The respective pairs of brackets carry grooved pulleys 43, 44 which furnish guides for pairs of cables 45, 46. The lower ends of the front cables are secured to eye bolts 47 (Fig. 11) at the ends of an equalizer bar 48. The lower ends of the rear cables 46 are similarly secured to eye bolts 49 (Figs. 4 and 9) at the ends of an equalizer bar 50.

The equalizer bar 48 has a central connection 51 to a treadle 52 (Fig. 11). The free end 53 actually comprises the treadle because this is intended to be stepped upon by the workman when the carrier is to be drawn back. The treadle is pivoted at 54 to one of the legs 2 of the frame. The equalizer bar 50 has a shank 55 suspended from it. This shank supports a weight 56. The weight may have a removable section 57, and the shank 55 can be made long enough to permit the addition of still another weight.

Although in most instances the weight 56 will be of a fixed size, yet instances can occur where it is desired to press the bottles up against the buffing wheels 12 with more or less pressure than is afforded by the fixed weight 56. Such occasions can be met by adding or subtracting sections to the shank 55.

This leads the description to the essential part of the invention which comprises the carrier generally designated 58 (Fig. 9). This carrier comprises a self-contained unit, and it has included in it every element necessary to reciprocate the bottles in the peculiar manner herein proposed. The carrier has a heavy foundation plate 59. The ends 60 of this plate (one being shown in Fig. 3) are notched at 61. The notched ends 60 are set upon and suitably affixed to the pitched seats 62 of a pair of side bars 63 (Fig. 12). The pitch of the seats 62 (Fig. 3) is of such a degree as to insure the positioning of the bottle rack (Fig. 2) perpendicularly to the selected radius 64 (Fig. 9) of the buffing wheel 12.

The reason for setting the foundation plate 59 at the pitch shown is to give the bottle rack (Fig. 2) a backward slant matching the position 55 of the line 65 (Fig. 9). The bottles are all thus held in place by gravity, and since the buffing wheel rotates in the direction of arrow a, none of the bottles will ever fall out.

The connection of the plate 59 to the side bars 63 is rigid. The setting of the plate at the pitch described produces projections 66, one of which is adapted to be engaged by the hook end 67 of a hold-back handle 68. This handle is pivoted upon a bolt 69 (Fig. 10) which is secured between an upstanding bracket 70 on the table top 4 and the nearest upward extension 7 of the box 6.

The side bars 63 carry wheels 71 (Fig. 1). Each of the side bars carries a pair of the wheels (Fig. 5). A guard plate 72 is interposed between each side bar and its pair of wheels. The guard plates are made quite long (Fig. 1), thus to catch most of any splashing from the box 6, and also to protect the wheels and rails. Since the construction of each of the four wheels is alike

and its relationship to the rails is the same, attention is directed to Fig. 19 for the details, the numerals there shown applying to matching parts in all of the views.

In Fig. 19 the side bar 63 is shown to have a heavy spindle 73 securely attached to it by the nut 74. Equivalent securing means can be used. The spindle 73 terminates in a race 75 for the ball bearings 76 which are inserted in a cavity and matching race 77 in the wheel 71. A nut or equivalent means 78 is screwed onto the spindle to maintain the wheel and spindle assemblage, a cover plate 79 finally being emplaced to protect the ball bearings from dust.

As well shown in Fig. 19, the wheel 71 is grooved. The V-groove is not necessarily adhered to, but has been found to adequately serve the purpose. Inasmuch as the wheel 71 runs on the rail 17 the latter actually comprises one of the pair of track rails (Fig. 12). No weight is imposed upon the rails 16, consequently these merely act as guards as already brought out. They prevent the carrier from jumping the track.

The near ends of the previously mentioned cables 45, 46 are attached to the guard plates 72 of the carrier, as shown in Fig. 5. Each attachment is of the same construction as in the instance of one of the cables 45. The end 80 of this cable (Fig. 6) is bent to fit the matching grooves 81, 82 in companion members 83, 84 (Fig. 8). These members are secured together and to the guard plate 72 by a bolt and nut 85.

The securing of the weight 56 to one end of the carrier 53 tends to move the latter in the direction of arrow b (Fig. 9). The movement is along the track 17 when not prevented by the hold-back handle 68.

The previously mentioned bottle rack (Fig. 2) consists of a board 86 which has knobs 87 to provide for its being lifted out of the machine. In practice a number of the boards are provided. The board 86 has a ledge 88 upon which the bottles 89 are stood, as shown. The ledge is continued at its ends to comprise upright side members 90 which limit the number of bottles to be inserted, and also prevent the end ones from slipping off sidewise. The bottles project slightly beyond the face of the ledge 88. The edge of the board 86 is chamfered at 91 adjacently to the necks of the bottles. This chamfer provides a throat in a sense, facilitating the introduction of powdered pumice stone or an equivalent buffering compound. The bottle board 86 has a metal reinforcement 92 (Fig. 2).

A rack plate 93 (Fig. 16) provides for the support of the bottle rack 86. The plate 93 has upright end cleats 94 to which guide strips 95 are attached. These strips overhang the cleats in such a way as to provide end passages 96 into which the ends of the board 86 are slid. The rack plate 93 has a plurality of lugs 97 along its lower edge on which the bottle rack 86 is rested. A shield 98 extends from the rack plate 93 to the foundation plate 59 (Figs. 9 and 17), to prevent spattering the mechanism behind the rack plate with buffering material.

Heads 99 rigidly secured to the rack plate 93 (Figs. 16 and 17) have pairs of matching passages 100 for a pair of slide rods 101. The ends of these slide rods are fixedly secured in brackets 102 on back of a pair of heads 103 (Fig. 14), of a cam plate 104. This plate is adapted to be reciprocated because of the cam action imparted to it by an eccentric 105. The plate 104 has a

frame 106 (Figs. 13 and 14) in which the eccentric revolves (Fig. 17).

Revolving the eccentric 105 causes the cam plate 104 to reciprocate vertically. To this end heads 103 have vertical passages 107 (Fig. 14) for the occupancy of spindles 108 rigidly affixed to and upstanding from the foundation plate 59 (Fig. 15). The passages 107 are capped at 109 (Fig. 15) to prevent dust from coating the moving surfaces.

Also rigidly secured to the foundation plate 59 is a roller standard 110 (Fig. 15). This standard has a journal 111 affixed to it (Fig. 17). A roller 112 is turnable on this journal. The roller occupies a position between a pair of guide rails 113 (Fig. 15). These rails are set at a 16 degree angle on a mount 113a which bridges the heads 99, although this setting is subject to variation in various buffering machines if it be found desirable to produce a more or less pronounced bias reciprocation of the rack plate 93.

From this statement it will be understood that the rack plate 93 is subject to a bias motion as it is reciprocated in the up and down directions.

25 In other words, the motion is on a diagonal in respect to the face of the buffering wheel 12. The source of the power which produces the motion is a motor 114 (Fig. 12). This motor is supported by a bracket 115 which is attached to one of the side bars 63. The motor shaft 116 carries a drive sprocket 117 which drives the sprocket 118 of a speed reducer 119 by means of a chain 120. The low speed shaft 121 of this reducer has the previously mentioned eccentric 105 affixed to it (Fig. 17). The speed reducer is mounted upon a plate 122 which is affixed to the foundation plate 59 and extends forwardly therefrom, as shown.

30 The operation is readily understood. The carrier 53 (Fig. 9) is the important moving part of the machine. It travels horizontally in respect to the frame 1, but inasmuch as the rack plate 93, cam plate 104 and directly associated parts are set at a pitch (Fig. 9) it follows that the bottles 89 are stood at an angle as presented to the surface of the buffering wheel 12.

35 The tendency of the weight 56 is to pull the entire carrier in the direction of arrow b (Fig. 9). The wheels 11 of the latter run on the track 17 (Fig. 12). As long as the hook end 67 remains in engagement with the projection 66 (Fig. 9) said motion is prevented.

40 The operator first sees to it that the bottle rack 86 (Fig. 2) is filled with bottles. He em- places the rack upon the rack plate 93. The next act is to step on the treadle 53 (Fig. 11). This pulls the carrier 53 toward the operator sufficiently far to enable the release of the pro- jection 66 from the hook end 67 when the handle 68 is pressed down.

45 The operator now lets up on the treadle 53, and in doing so permits the weight 56 to engage the bottles with the buffering wheel. As the eccentric 105 revolves in the frame 106, a true up and down motion is imparted to the cam plate 104. This motion is compelled by the guidance of the upright spindles 108.

50 The cam plate 104 carries the rack plate 93 with it. This is due to the connection which the sliding engagement of the rods 101 with the heads 99 affords. But instead of the rack plate 93 partaking of the true up and down motion of the cam plate 104, it is compelled to move on a bias because of the engagement of the angled guide rails 113 with the relatively fixed roller

112. The necessary sliding occurs on the rods 101, and the bottles are moved on a bias across several of the felts 22, insuring a thorough polishing operation and preventing any possibility of wearing tracks in the surface of the glass as might occur when the felts remain in unvarying relationship to the positions of the bottles.

I claim:

1. A buffering machine comprising a frame, revoluble buffering means on the frame with which an article is to be contacted, rails fixed on the frame, being inclined toward the buffering means, a wheeled carrier traveling rectilinearly upon the rails toward said buffering means and having the following elements mounted thereon for travel therewith as a unit, a plate upon which a series of the articles is emplaced for contact with said buffering means, said plate being perpendicular to the carrier and thus standing at a backward pitch, means embodied in the carrier for imparting a biased reciprocatory motion to said plate so as to strike the articles diagonally across the buffering means, and a source of motive power for said motion imparting means also on the carrier; and a weight guided on the frame and having a connection to the carrier for constantly tending to hold the carrier and the parts mounted thereon as a unit toward the buffering means and thus press the articles against the latter.

2. A buffering machine comprising revoluble buffering means with which an article is to be contacted, a pair of plates upon one of which a series of the articles is emplaced in contacting relationship to the buffering means, rotary motion means to actuate the second plate of said pair, guide means for the second plate confining its motion to a plane rectilinear with the plane of revolution of the buffering means, a slide coupling between the plates of said pair, a roller fixed relatively to said plates, and guide means on said one plate, engaging opposite sides of the roller and being set on a bias to said planes to bias the motion of said one plate.

3. A buffering machine comprising buffering means with which an article is to be contacted, a pair of plates by one of which a series of the articles is carried in contact with the buffering means, separate means for the respective plates on which said plates are respectively slidable crosswise and vertically of the buffering means, guide means for said one plate and a relatively fixed element with which said guide means coacts, converting the composite vertical and crosswise sliding thereof into a biased motion to strike the articles diagonally across the buffering means, and means to impart motion to the second plate of said pair.

4. In a buffering machine, a pair of plates, separate sliding supports for each of the plates, coupling means between said plates of which one of said supports is a part, the respective axes of sliding being at right angles to each other, a motor-driven speed reducer having an eccentric, a frame on one of the plates in which the eccentric is operable to reciprocate the respective plate, angle guide means on the other plate, and means stationary in respect to said plates, engaging the guide means to bias the motions of the respective plate as produced by the reciprocated plate.

5. In a buffering machine, manipulation means for supporting and reciprocating an article to be buffed, carrier means for said manipulating means including a foundation plate, wheeled side bars having pitched seats on which the foundation plate is emplaced to dispose said manipulating means on a slant, said seats defining projections because of their pitch, means to pull the carrier means in one direction, and detent means engageable with at least one of the projections to detain the carrier means.

6. In a buffering machine, the combination of a pair of plates, means on one of the plates to retain an article rack, means on the second plate of said pair in which an eccentric is operable, heads on each of the plates, the respective heads having passages at angles to each other, slide rods carried by the heads of the second plate occupying the passages in the heads of the first plate, relatively fixed erect spindles occupying the passages in the heads of said second plate, an element which is fixed relatively to both plates, and diagonal guide means carried by the heads of said one plate, coacting with said fixed element to produce a bias movement of said one plate in response to a vertical movement of the second plate.

7. In a buffering machine, a bottle rack comprising a board having a ledge constituting an article support, side members in extension of said ledge to retain the articles, and a chamfer on an edge of the board being directed toward the ledge to guide the introduction of a polishing agent.

8. In a buffering machine, a rack plate having lugs for the support of a rack, means at the ends of the plate for slidably retaining an article board, heads affixed to the rack, a mount bridging the heads, and a pair of guide rails attached to the mount being located on a pitch in respect to said mount.
